UNITED STATES PATENT OFFICE.

HENRY A. GOEBLER, OF CONNERSVILLE, INDIANA.

ADVERTISING DEVICE.

No. 895,085.

Specification of Letters Patent.

Patented Aug. 4, 1908.

Application filed April 9, 1906. Serial No. 310,862.

To all whom it may concern:

Be it known that I, HENRY A. GOEBLER, a citizen of the United States of America, and a resident of Connersville, in the county of 5 Fayette and State of Indiana, have invented certain new and useful Improvements in Advertising Devices, of which the following is a specification.

This invention relates to certain improvements 10 in advertising devices and more especially in that class of such devices wherein are employed means for producing illusory optical effects for directing attention to the advertisement, and the object of the invention is to provide a device of this character of a simple and comparatively inexpensive nature wherein an enhanced illusory effect is produced so that the value of the device for advertising purposes is greatly increased.

20 The invention consists in certain novel features of the construction and combinations and arrangements of the several parts of the improved advertising device, whereby certain important advantages are attained 25 and the device is rendered simpler, cheaper and otherwise better adapted and more convenient for use, all as will be hereinafter fully set forth.

The novel features of the invention will be 30 carefully defined in the claims.

In the accompanying drawings which serve to illustrate my invention—Figure 1 is a fragmentary perspective view showing the appearance of the improved advertising device when set up in position for use; Fig. 2 is a sectional view taken vertically through the supporting surface whereon the device is applied for use, the improved advertising device being, itself, shown in side elevation; 35 Fig. 3 is a view similar to Fig. 2, the plane of the section being extended, however, centrally through the body or casing of the improved advertising device to illustrate certain features of construction of the device within 40 said casing; Fig. 4 is a rear elevation of the casing of the improved advertising device illustrating the structure and arrangement of the means for attaching the same to the supporting surface; Fig. 5 is a view similar 45 to Fig. 4, and showing a modified, and in some situations, preferred, formation of the means for attaching the device to the supporting surface; Fig. 6 is a fragmentary sectional detail view showing the construction 50 and arrangement of the wedge-shaped member of the attaching means of the device;

Fig. 7 is a fragmentary detail view showing the bail upon the casing or shell of the device for engagement with said wedge-shaped attaching member; Fig. 8 is a detached perspective view showing a modified construction of an attaching member adapted to be cemented or otherwise attached to the supporting surface for engagement with the wedge-shaped attaching member seen in Fig. 6 for retaining the improved advertising device upon the supporting surface; Fig. 9 is a perspective view showing a preferred sign supporting means forming part of my improvements, and Fig. 10 is an enlarged fragmentary sectional detail view showing certain features of construction of a sign adapted for employment in connection with the improved advertising device as will be hereafter explained.

In these views 1 represents the supporting surface on which the improved advertising device is secured, said supporting surface 1 being formed of a plane glass mirror or similarly highly polished plate or sheet which is 20 vertically sustained, and 2 represents the shell or casing of the advertising device attached upon the said surface 1 and herein shown as made in the form of a half barrel, being arranged to project from the plane face 85 of the mirror or other polished surface 1 in such a manner as to be reflected therein so that to an observer the reflection of said half barrel shall form a reversed reproduction and continuation of the casing whereby the device 90 will give the illusion of a complete barrel suspended in the air without visible sustaining means.

Upon the casing or half barrel 2 of the improved advertising device is secured a sign 95 section 3, supported in any suitable manner upon the top of said casing and extended in the direction of the length thereof with one end abutting upon the surface of the mirror 1, and by preference, said sign-section will embody 100 the construction shown in detail in Fig. 10, comprising a vertically extended board or strip 4 upon the opposite sides whereof are held paper or other strips 5, 5 having vertical V-shaped corrugations whereby each strip 105 has produced upon it forwardly-inclined surfaces 6, 6 directed away from the mirror 1 and adapted to be directly visible to an observer and rearwardly-inclined surfaces 7, 7, directed toward the mirror 1 and adapted to 110 be visible to an observer only after reflection from said mirror 1.

Upon the forwardly inclined surfaces 6 6 of the strips 5 are printed or otherwise formed certain letters or characters as shown at 8 in Fig. 1 and 10 in Fig. 2, the letters or characters 5 8 in Fig. 1 constituting the beginning of the word "Extra", and upon the rearwardly directed surfaces 7 of said strips 5 are printed or otherwise produced certain other characters which are adapted to be reflected in the 10 mirror 1 as seen at 9 in Fig. 1 to form the continuation of said word "Extra", when viewed by the observer so that the illusion is given of a sign board bearing that word or other desired symbol extended above the barrel previously 15 referred to as being shown by the reflection of the casing 2 in mirror 1. The characters 10 at the opposite side of the sign 3 form the ending of the word "Extra" and at this side of the sign board the rearwardly-directed 20 surfaces 7 have printed or otherwise produced upon them other characters which, when reflected in mirror 1 complete said word so that from whichever side the device is viewed, a similar illusion will be produced.

25 By preference the means for attaching the improved advertising device upon the mirror or other polished surface 1 will be housed and hidden within the casing 2 so as to not be visible to the observer and the end or outer 30 head of the half barrel like casing 2 is preferably formed with a transparent or translucent glass plate as shown at 11 upon which may be arranged any desired letters or marking, while within the hollow of said casing 2 is 35 arranged an incandescent lamp 12 or other illuminating device so that the lettering or marking upon the end surface 11 may be illuminated to add to the appearance of the improved device.

40 The attaching means comprises a plate or frame 13 of metal or the like as shown in Figs. 4 and 5, there being pneumatic sucker-pads 14, carried upon rods attached to said plate or frame as seen at 15 and said sucker-pads are adapted to be held in a well known way by atmospheric pressure upon the surface of the mirror 1 for retaining the plate or frame 13 in place, and said frame or plate 1 is provided with a vertical guide-way formed 45 between spaced flanges or projections 16, 16 and wherein is designed to be engaged a wedge-shaped attaching-member 17, which may be pivoted or hinged as shown at 18 in Figs. 3, 4 and 5, within the shell or casing 2 so as to depend from the top thereof in position for convenient engagement with the guide-way between projections 16. By this construction 50 it will be seen that when the frame or plate 13 is attached to the mirror or other support 1 by means of its sucker-pads 14, the shell or casing 2 may be applied over the same with its hinged wedge-like member 17 engaged in the 55 guide-way of said frame for securely retaining said shell or casing 2 in position upon the 60 mirror, and attaching means being wholly 65

inclosed within said shell or casing and being altogether invisible to the observer.

In Figs. 6 and 7 is shown a modified arrangement wherein the wedge-like member 17 is detachably-connected with the shell or casing 2 instead of having hinged-connection therewith, said wedge-like member having, in this construction, an integral bent shank 19 adapted to be passed for detachable engagement through a bail or loop 20 carried by the shell or casing 2 so that, when so engaged, the wedge-like member may be passed in the guide-way of the attaching plate or frame 13 for holding the shell or casing 2 upon the mirror 1 as above described.

70 In Fig. 8 is shown another modified construction wherein the frame or plate 13 provided with the sucker-pads 14 for attachment to the mirror 1 is dispensed with by the employment of a plate 21, pressed from metal or the like and provided with a superficial coating of adhesive substance such as cement, glue or the-like by means of which it is caused to adhere to the mirror or other support 1. Plate 21 is also provided with a guide-way 80 having an inclined rear wall 22 in which is adapted to be received the wedge-shaped member 17 hinged or otherwise secured within the casing or shell.

85 The improved attaching means as above 90 described permits of securely attaching the advertising device to the mirror or other supporting surface and when so attached, the shell or casing 2 is capable of being conveniently disengaged so that the device may be 95 readily taken down for repair or other purpose.

95 In connection with the shell or casing 2 I prefer to employ a device for supporting such a sign-board as that shown at 3 upon the top of the shell or casing, and said sign supporting device may be conveniently constructed as seen in Figs. 1 and 2, wherein 3* 100 is a horizontal, grooved guide-way or channeled bar directly resting at its inner end on the shell or casing 2 and supported at its outer end on an upright 3° of arc or concave shape along its bottom to conform to the contour of the said shell or casing on which it, in turn, rests. The sign 3 is slid lengthwise 105 into place in the guide-way 3* until its inner end contacts with the mirror surface 1. Another supporting device for said sign 3 as seen in Fig. 9, may be made from a strip of metal 23, having spaced lugs 24 at its upper part 110 between which the edge portions of the sign board may be engaged. The ends 25 and 28 of strip 23 are bent downwards and have tongues 27, 27, for detachable-engagement 115 with bails or loops 26, 26 upon the shell or casing so that the strip 23 may be detachably held to the casing when the same is disconnected from the mirror or other supporting surface 1, but will be securely held against 120 accidental disengagement from the shell or 125 casing.

casing 2 when the device is in position upon the mirror or other supporting surface 1, by engagement of the inner end of strip 23 and of the signboard 3 carried thereby with said 5 supporting surface or mirror.

From the above description of my improvements it will be evident that the improved advertising device is of an extremely simple and comparatively inexpensive nature and is especially well adapted for use by reason of the convenience and security with 10 which the same may be attached upon mirror and other polished surfaces without liability of marring or in any way injuring the 15 supporting surface, and also by reason of the fact that the attaching means is wholly inclosed and hidden within the shell or casing so as to detract in no way from the illusion or impression upon the observer.

20 It will also be obvious from the above description of my improvements that the device is capable of considerable change without material departure from the principles and spirit of the invention and for this reason 25 I do not desire to be understood as limiting myself to the precise form and arrangement of the several parts of the device as herein set forth in carrying out my invention in practice except as required by the scope of the 30 appended claims.

It is still further obvious that the advertising device comprising the casing and sign-board could be supported in contact with the mirror-surface without the use of the internal suction and adhesive means, by simply 35 resting it on any object that stands in front of the said mirror, and the same illusive effect secured.

Having thus described my invention, 40 what I claim and desire to secure by Letters-Patent is—

1. A device of the character described comprising a part adapted for attachment to a supporting surface of polished or reflecting material and provided with suitably spaced projections at either side thereof, such projections forming a vertical guide-way between them with an inclined rear wall, and a cylindrical shell or casing having 45 50 a wedge-shaped member or tongue adapted for detachable-engagement in the guide-way

between said spaced side projections and the inclined rear wall to draw the shell or casing snugly against the supporting surface.

2. A device of the character described 55 comprising a shell or casing, a sign-board adapted to be supported upon the shell or casing and attaching means for retaining the sign board upon the shell or casing and comprising a strip connected with the sign-board and devices upon the shell or casing for detachable-engagement with said strip.

3. A device of the character described comprising a shell or casing, a sign-board adapted to be supported on the shell or 60 casing and attaching means for holding the sign-board upon the shell or casing and comprising a strip connected with the sign-board and provided with downwardly bent end portions the extremities of which have forwardly 65 directed parts and loops carried by the shell or casing and with which said forwardly-directed extremities are adapted for detachable engagement.

4. A device of the character described 75 comprising a hollow shell or casing one end of which is adapted for flush-engagement upon a polished supporting surface and the other end of which is provided with a translucent plate adapted to receive an advertising 80 symbol, attaching means housed in the shell or casing for detachably-holding the same upon the polished supporting surface and an illuminating device within the shell or casing to illuminate the translucent plate at the end 85 thereof.

5. An advertising device comprising a shell or casing having attaching means for holding it upon a supporting surface of polished material and a sign-board carried by the 90 shell or casing with vertical corrugations having forwardly and rearwardly directed surfaces which are provided, respectively, with symbols or characters, the symbols or characters on the rearwardly directed surfaces being adapted for reflection from said 95 polished supporting surface.
